DANCING DOLL

Arthur Wessan, 905 Longacre Ave., North Woodmere,
Long Island, N.Y.

Filed Aug. 27, 1965, Ser. No. 86,739

Term of patent 7 years

(Cl. D34—4)

FIG. 2 is a rear view thereof,
FIG. 3 is a top plan view thereof, and
FIG. 4 is a side elevational view thereof.
I claim:
The ornamental design for a dancing doll, substantially as shown.
